UNITED STATES PATENT OFFICE.

FRANK C. BURKHART, OF OMAHA, NEBRASKA.

LIGHTING-FIXTURE.

1,163,208.

Specification of Letters Patent.

Patented Dec. 7, 1915.

Application filed May 24, 1915. Serial No. 30,029.

To all whom it may concern:

Be it known that I, FRANK C. BURKHART, a citizen of the United States, residing in the city of Omaha, in the county of Douglas and State of Nebraska, have invented certain new and useful Improvements in Lighting-Fixtures, and have described the same in the following specification, illustrated by the accompanying drawings.

10 My invention relates to that class of dependent lighting fixtures which are commonly used in distributing artificial illumination by the semi-indirect method of direct radiation combined with downward reflection, and which commonly comprises a translucent bowl containing the source of light, and a hanger suspending the bowl.

The principal objects of the invention are these: to render the hanger of such a fixture adjustable for use with bowls of different sizes and varied makes and patterns; to adapt the hanger to be used with a variable number of suspending chains; and with a variable number of lamps; to prevent the hanger from throwing on the bowl any visible shadow; to suspend the bowl solely by internal engagement therewith, without the aid of clamps and without binding stress; to prevent the hanger from chipping the edge 30 of the bowl; to obviate all need of perforating the bowl; to support the bowl uniformly and continuously all the way around; to avoid cracking the bowl by thermic deformations; to render the bowl removable from 35 the hanger, for cleansing or for substitution, without disturbing the wiring of lamps therein; and in general to produce a superior lighting fixture of the specified class. To accomplish these objects, I incorporate 40 in my improved lighting fixture, as parts thereof, a contractile and distensible perforated ring for the immediate support of the bowl, and a plurality of socket finger hooks for the support of the rings; these 45 hooks being suspended from above and affixed to the ring by adjustment at various distances apart.

In the accompanying drawings, illustrating the best manner in which I have contemplated applying the principles of my invention, Figure 1 is a side elevation of a lighting fixture which is constructed in accordance with these principles. Fig. 2 is a central vertical section of the same, together 55 with a lamp and lamp wire in position therein. Fig. 3 is a plan of the bowl-supporting

ring, together with the socket hooks and a lamp which are carried thereby. Fig. 4 is a vertical section on the section line in Fig. 3.

In the illustrated specimen of my invention, the translucent bowl, open at the top, the horizontally disposed ring supporting the bowl, the finger hooks carried by the ring, the chains suspending the ring by these hooks, the lamps carried by these hooks respectively, and the conductive wires to the lamps, are denoted by the numerals 1 to 6 respectively. The bowl 1 is of any preferred type, having at the top a contracted mouth formed by the reentrant lips 7. The ring 2 is a thin band of elastic metal, perforated by numerous bolt holes 8, which are uniformly spaced apart and are disposed in a central line from end to end of the band. By means of a changeable lap joint, uniting 75 the strip with itself and comprising the screw bolts 9, inserted in the appropriate bolt holes 8, this ring is adjusted in size to fit loosely under the lips of the bowl which is suspended thereon. Each of the finger 80 hooks 3 comprises the terminal base 10 for immediate attachment to the ring, the usual screw nipple 11, to engage the lamp socket, and the intermediate connecting strip 12, which is bent inward from the base so as 85 to avoid contact with the lip 7, and has an arched portion 13 to engage the chain 4. These hooks, being of such a variable number, and at such a variable distance apart, as may be desired, are adjusted and secured 90 severally to the inside of the ring by the screw bolts 14 inserted through the appropriate bolt holes 8. The chains 4, engaging the arches 13 respectively, are suspended in any usual or convenient manner from an 95 overhead point of attachment which is not shown in the drawings. The lamps 5 are attached to the socket fingers respectively, or to as many of them as may be desired, and are connected with a source of current by 100 the wires 6, following the chains 4, all in the usual manner. To avoid each other the lamps may be turned aside, as shown in broken lines in Fig. 3, by flexing the connecting strips 12 of the socket hooks. 105

The described hanger is adjustable to different bowls by changes in the size of the ring, effected at the lap joints by relocating the bolts 9 in the bolt-holes 8; is adjustable to be used with any desired number 110 of suspension chains and lamps by removing some, or adding more, of the socket

hooks, and spacing the latter uniformly by relocating the bolts 14; is prevented from throwing a visible shadow on the bowl by the numerous ring perforations 8 and by the narrowness of the contact between the bowl and the top edge of the ring on which it hangs; while in obvious ways the described fixture accomplishes the specified objects of the invention in all other particulars.

10 I claim as my invention—

1. A lighting fixture of the specified class, comprising a perforated and lap-jointed ring adapted to support internally a bowl resting immediately on the top of the ring, and a plurality of socket fingers fastened to the ring, and adjustable thereon.

2. A lighting fixture of the specified class, comprising a bowl, a rigid band ring of adjustable size engaging the inside of the

20 bowl, and a plurality of socket fingers fastened to the inside of the ring within the

bowl for the support of lamps and as means of suspending the ring.

3. A lighting fixture of the specified class, comprising a band ring of adjustable size 25 for the internal support of a bowl suspended thereon, and a plurality of adjustable socket fingers attached to the inside of the ring for the support of lights within the bowl.

4. A lighting fixture of the specified class, 30 comprising a band ring disposed cylindrically about a vertical axis, and having a plurality of radial perforations for the passage of light, light-supporting means attached to the ring internally, means for suspending the light-supporting means, and a translucent bowl containing the ring and resting thereon.

Witness my signature at Omaha, Nebraska, May 22d, 1915.

FRANK C. BURKHART.
